UNITED STATES PATENT OFFICE.

WILLIAM H. MUZZY, OF DAYTON, OHIO.

TRACTOR-SWING.

1,121,029.

Specification of Letters Patent.

Patented Dec. 15, 1914.

Application filed May 2, 1912. Serial No. 694,730.

To all whom it may concern:

Be it known that I, WILLIAM H. MUZZY, a citizen of the United States, residing at Dayton, in the county of Montgomery, and State of Ohio, have invented certain new and useful Improvements in Tractor-Swings, of which I declare the following to be a full, clear, and exact description.

This invention relates to improvements in swings and has more particular relation to improvements in porch swings.

One of the principal objects of the invention is to provide a porch swing with means for resting the feet which may be used to cause the swing to swing back and forth.

A further object is to so construct the swing as to give it a practically rigid back while still allowing the swing to be flexibly suspended.

The invention also has other objects all of which will be apparent from the following description and the accompanying drawings in which latter:

Figure 1 represents a central vertical section through the devices embodying my invention. Fig. 2 represents a top plan view of the same and, Fig. 3 represents a detail front elevation, partly broken away of the foot board, one of the tractors and its supporting bracket.

The base of the swing comprises a frame 1 which supports a mattress or seat 2 having any suitable springs, not shown. The frame is suspended at each end by canvas sides 3 which are secured about side rails 4 through which the supporting ropes 5 are passed; these ropes on each side converging to a ring 6 supported by a rope 7 which is secured to the ceiling of the porch.

The back rest 8 is a rigid frame suitably tufted and hinged at its lower edge to the rear edge of the frame 1. The upper corners of the back are provided with pivoted hooks 9 which are arranged to hook over headed pins 10 in the side rails 4 to hold the back in position but allow of its being doubled down upon the seat 2 when desired to protect the tufting of the seat and the back from rain which beats in upon a porch at times.

The foot rail or board 11 is supported at each end by wire wheel 12 having a suitable rubber tire and journaled on a bolt 12 which is secured to a bracket iron 13. These irons are secured by screws to the under side of

the foot rail 11. Rods or bars 14 are secured at their forward ends to the under side of the foot rail and are pivoted at their rear ends to the side bars of the frame 1 near the back of the latter.

The operator in the swing rests with his back against the back 8 and his feet on the foot rail 11. The center of gravity is downward from the rope 7. If the operator now

presses upon the foot rail 11 with his feet he will naturally throw his weight against the rigid back 8 and the center of gravity will be shifted to the rear which will cause the swing to swing forward. The operator naturally relieves the pressure on the foot rail 11 as the swing swings forward and the swing returns when the operation is repeated.

A very slight pressure on the foot rail will cause the swing to gently oscillate and at the same time the feet are comfortably supported and not dragging on the floor as is usual in this class of swing. Further,

even though the operator is placed near one side of the swing and pushes on the foot rail near one end the swing will still swing true and not start a sidewise oscillation such as would occur if the operator pushed on the porch floor as at present in such swings.

The tractors or wheels 12 cause the swing to swing true at all times by their engagement with the porch floor. These wheels by resting upon the porch floor provide the necessary purchase for the feet of the operator to push against just as if he were pushing upon the floor itself and at the same time move with the swing so that the feet of the operator have a comfortable rest and are always ready for the pushing operation.

The location of the foot rest in relation to the swing is such that when the swing swings to the rear the operator's legs are drawn together as in rowing and he straightens them out as the swing swings forward and can thus exert considerable power without much exertion.

It will, of course, be understood that the swing can be suspended in the frame, or from the ceiling of a porch, or in any desirable manner.

It will be observed that the forward pull on the bars 14 is communicated to the frame 1 to the rear of its center of gravity and this frame is thus tilted and tends to throw the weight of the operator to the rear against the back 8. This action is added to the

natural back pressure of the operator when pushing on the foot board, to cause the swing to oscillate.

The tractor wheels being shod with rubber practically make no sound and the whole swing swings as free as if it had no attachment contacting with the floor at all.

Having thus described my invention what I claim as new and desire to secure by Letters Patent is:

The combination with a swing suspended to swing freely, of a foot board supported

by spaced tractor wheels, spaced guide bars on the foot board and so connected to the swing as to be capable of vertical pivotal movement only to prevent any side movement of the swing.

In testimony whereof I affix my signature in the presence of two witnesses.

WILLIAM H. MUZZY.
